(57) **CLAIM**

The ornamental design for a peritoneal dialysis cycle and cassette combined, as shown and described.

DESCRIPTION

FIG. 1 is a first end perspective view of a peritoneal dialysis cycle and cassette combined;

FIG. 2 is a first end perspective view of the cycler of FIG. 1, with a cycler cassette access door open;

FIG. 3 is an opposite, second end perspective view of the cycler of FIG. 1;

FIG. 4 is a front view of the cycler of FIG. 1;

FIG. 5 is a first end elevation view of the cycler of FIG. 1;

FIG. 6 is a second end elevation view of the cycler of FIG. 1; and

FIG. 7 is a rear view of the cycler of FIG. 1.

FIG. 8 is a perspective view of a cassette for use with the cycler of FIG. 1;

FIG. 9 is a front elevation of the cassette of FIG. 8;

FIG. 10 is a rear view of the cassette of FIG. 8;

FIG. 11 is a right side view of the cassette of FIG. 8;

FIG. 12 is a left side view of the cassette of FIG. 8;

FIG. 13 is a top plan view of the cassette of FIG. 8; and,

FIG. 14 is a bottom plan view of the cassette of FIG. 8.
